CLAIM

The ornamental design for a beverage container assembly, as shown and described.

DESCRIPTION

FIG. 1 is a top plan view of the middle piece of our design of a beverage container assembly, including the center strainer in broken lines;

FIG. 2 is a bottom plan view of the middle piece beverage container assembly;

FIG. 3 is a cross-section side view of the middle piece beverage container assembly, taken along line 3-3 in FIG. 1; and, FIG. 4 is a perspective view of our design of the beverage container assembly including a transparent wrapper in accordance with our design.

The beverage container assembly has generally cylindrical symmetry. The separate components are shown to illustrate aspects, which are not apparent from the assembled views. The broken lines depict portions of the beverage container assembly that form no part of the claimed design.
